United States Patent Office

Des. 224,213
Patented July 11, 1972

224,213

SHELTER

Robert S. Wormser, Hillsdale, Mich., assignor to Game
Time, Inc., Litchfield, Mich.

Filed Mar. 18, 1971, Ser. No. 125,904

Term of patent 14 years

Int. Cl. D25—03

U.S. Cl. D13—1

FIG. 1

FIG. 2

FIG. 1 is a right side elevational view of a shelter showing my design, the left side appearing as the mirror image thereof,

FIG. 2 is a rear elevational view of my design,

FIG. 3 is a front elevational view, and

FIG. 4 is a top plan view of my design.

I claim:

The ornamental design for a shelter, substantially as shown and described.
